UNITED STATES PATENT OFFICE.

GEORGE M. BALL, OF BROOKLYN, ASSIGNOR, BY DIRECT AND MESNE ASSIGNMENTS, TO JAMES B. ATHERTON, LOUIS D. BECK, AND ANTHONY DEY, ALL OF NEW YORK, N. Y.

WIRE-TWISTING MACHINE.

SPECIFICATION forming part of Letters Patent No. 443,491, dated December 30, 1890.

Application filed October 31, 1889. Serial No. 328,739. (No model.)

To all whom it may concern:

Be it known that I, GEORGE M. BALL, a citizen of the United States, residing in Brooklyn, county of Kings, and State of New York, have invented certain new and useful Improvements in Wire-Twisting Machines, of which the following is a specification.

The object of my invention is to provide a machine for rapidly twisting a pair of electrical conductors that have been covered with insulation in such manner that the twisted wires will not kink and that there will be practically the same length of wire in each strand. The ordinary arrangement heretofore employed, in which bobbins carrying the wires to be twisted are mounted upon a common revolving frame, is necessarily slow, and the results are not altogether satisfactory.

In my improved machine one wire is drawn from a bobbin inclosed by a flier or revolving frame, while the other is applied spirally around it from the revolving flier, which latter is of peculiar construction. As the two wires leave this part of the apparatus one is longer than the other, and in order to insure a uniform mutual twist of both wires so that they shall both be of the same length I pass the wires over stretching-drums, the operation of which upon the wires is such as to equalize them in length and twist, the additional length of wire for this purpose being drawn from its bobbin by the draft of the drums and the strain of the other wire.

My invention consists in the improved combination of devices set forth in the claims.

In the accompanying drawings, Figure 1 is a side elevation, partly in section, of a machine embodying my invention; Fig. 2, an end elevation thereof; Fig. 3, a plan view partly broken away and with some of the parts omitted. Fig. 4 is a detail view showing the bobbin in elevation and the bobbin-carrying frame and flier in section.

A B C D are the frame-standards.

In the standards B and C a revolving frame or flier E, whose trunnions e e' are hollow, is journaled. This frame is preferably of pear shape, as shown, and one side of it is hollow, and the bore thereof communicates with the

hollow trunnions e e' . The pulley F is mounted upon the hollow trunnion or shaft e' , and power may be applied to the pulley by a suitable belt to revolve the frame E. Within the frame E a yoke G is pivoted upon trunnions g g' , one of which g' is hollow and coincides with the bore of the trunnion or shaft e . The bobbin-carrying frame G is balanced on its trunnions and is free to adjust itself thereon. Within the frame G a bobbin H of wire may be removably mounted, and the wire x therefrom passes directly through trunnion g' and the hollow shaft or trunnion e in a straight line to the stretching-drum S'. The other wire y is brought from a reel (not shown) through the hollow shaft e' and through the hollow side or guide e^2 of the revolving frame or flier E, and through the opposite hollow trunnion e of said frame, and then to the stretching-drum with the wire x . A gear-wheel I on the end of the hollow shaft e' , into which the wire y is fed, gears with the wheel I' on the counter-shaft I ^{2} , carrying a worm i , gearing with a pinion i' on the shaft of the first stretching-drum S'. The first stretching-drum is thus driven from the pulley F, which revolves the flier E. The two wires x y are carried back and forth over the stretching-drums S S', whose peripheries are provided with grooves, as presently described, and finally the twisted wires pass to a storage-reel. (Not shown.) The wires x y having been drawn out through the hollow shaft e and around the stretching-drums S S', power is applied to the pulley F, and the stretching-drums draw the wires through the machine. The wire x is drawn through its guide x' in the trunnion g' straight from the bobbin H, while the wire y , passing through the hollow side or guide e^2 of the revolving flier E, is applied or wound spirally around the wire x . The wires thus twisted pass to the stretching-drums, the draft of which equalizes the twist and draws sufficient wire from the bobbin H to permit of the equalization of the twist and insure that both strands are of the same length.

As seen in Fig. 3, the peripheries of the drums S S' are provided with circumferential

grooves *f*, which gradually decrease in depth from one end side of the drum to the other. The twisted wires run first into the deepest groove, and then successively in the shallower grooves, being thereby sufficiently stretched without being subjected to any sudden strain.

A proper tension may be placed upon the bobbin *H* to prevent slack or prevent the wire running ahead of itself by means of a tension-screw *h*, working in one side of the frame *G*, and provided upon its inner end with a felt or leather washer *h'*.

The details of construction are plain from the drawings, and a more detailed description is therefore unnecessary. The flier may be cast of a single piece of metal or may be composed of detachable parts, and in order to balance it one side if solid may be made of smaller cross-sections; but I prefer to make both sides hollow and form them of seamless tubing, as shown in Fig. 4.

The flier is preferably pear-shaped in side elevation, and the bobbin is hung in its frame at the larger end of the flier, which has sufficient space at this end between its arms to accommodate it. The converging ends of the arms come together gradually and apply the strand with the proper inclination to the core. The flier is similarly shaped on opposite sides, so as to have a perfect balance.

Having thus described my invention, what I claim as new, and desire to secure by Letters Patent, is—

1. The combination, substantially as hereinbefore set forth, of a flier having hollow trunnions and a tubular side piece or guide connecting the trunnions, through which a strand is fed, a bobbin-holder around which the flier revolves, and stretching-drums for drawing the strands from the bobbin and the flier and imparting to the twisted strands a uniform length.

2. The combination, substantially as hereinbefore set forth, of the standards, the pear-shaped flier having tubular side pieces, and hollow trunnions mounted in the standards, the bobbin-holder hung loosely within the flier, a die at one end of the flier, through which a strand from the bobbin passes, stretching-drums, the upper surface of one of which is in the same parallel plane as the die, a driving-pulley for revolving the flier, and gearing connecting said pulley with the stretching-drums.

In testimony whereof I have hereunto subscribed my name.

GEORGE M. BALL.
